(57) **CLAIM**

We claim the ornamental design for a media depository, as shown and described.

DESCRIPTION

FIG. 1 is a front perspective view of a media depository showing our new design.

FIG. 2 is a back perspective view thereof.

FIG. 3 is a first side elevational view thereof.

FIG. 4 is a second side elevational view thereof.

FIG. 5 is a front end elevational view thereof.

FIG. 6 is a back end elevational view thereof.

FIG. 7 is a top plan view thereof; and,

FIG. 8 is a bottom plan view thereof.

The broken line showing of the key is for illustrative purposes only and forms no part of the claimed design.
